BASKET DISPLAY

Henry Ziemmerman, Chicago, Ill., assignor to
 Chicago Cardboard Company, Chicago, Ill., a
 corporation of Illinois

Application December 30, 1935, Serial No. 56,664

2 Claims. (Cl. 229—41)

This invention relates in general to a folding or collapsible open container or receptacle, preferably in the form of an upwardly flaring basket, made of flexible material such as cardboard, having at least one of the sections extending upwardly above the others and providing a display plate for advertising.

An important object of the invention is in the provision of a foldable display which may be easily set up and collapsed to substantially flat condition when not in use.

Another feature of the invention is in the provision of an interlocking bottom structure which automatically engages the inwardly sloping sides from the inside thereof, thus providing a bottom which is not easily pushed through the sides of the basket even though a heavy load is placed therein.

A still further object of the invention is in the provision of a basket display of this kind made of one or more pieces of sheet material cut, scored and foldable to fit together as herein shown and described.

In the drawing, Fig. 1 is a perspective of a basket display embodying this invention, in unfolded or set-up position;

Fig. 2 is a sectional view showing the interengagement of the upwardly extending bottom flaps;

Fig. 3 is a transverse section taken just above the bottom flaps;

Fig. 4 is a section taken on the line 4—4 of Fig. 3;

Fig. 5 is a detail section on the line 5—5 of Fig. 2 of one interlocking engagement between the bottom flaps; and

Fig. 6 shows a one-piece blank from which the structure is made.

In displays of this kind it has been proposed to provide the bottom with downwardly formed flaps which constitute a support, with upwardly formed flaps which must abut and with flaps having hooks adapted to engage in corresponding slots in the basket wall structure which are objectionable for the reasons that it is difficult to fold the downwardly turned flaps inwardly at the bottom and when they do engage the base upon which the display is supported they tend to rip and tear loose; the abutting engagement of the ends of the flaps is difficult to insure because if they are not in alignment they constitute no support for the bottom, which may slip through the perforation at the sides if any weight is applied to the bottom; and the hooks may be difficult to engage with the perforations, or if they become bent or

broken the bottom will be substantially without any support.

The present invention overcomes all of these objections by providing the bottom with interengaging flaps which are inclined to insure their inter-engagement as soon as the bottom is pressed downwardly within the sides, thereby automatically locking the bottom against any reduction in size which would make it possible for the bottom to be pushed through the bottom opening of the sides unless the structure itself is broken.

As these wedging inter-engaged flaps are made of somewhat resilient material, the bottom may tend to rise in the display unless some additional weight is carried by the bottom and to prevent this a lug or projection is stuck out of one of the flaps adapted to engage below the edge of one of the basket sides for holding the bottom in its extended and downward position.

Referring now more particularly to the drawing, this display may be made of a single blank of material as shown in Fig. 6, or of a number of pieces scored, cut and attached to form a similar structure. This blank comprises a main display plate 10 having sides 11 and 12, one provided with a gluing tab 13 and the other with extension sides 14, 15 and 16, all tapered from top to bottom so that when the ends of the sides are connected they will form a hollow open structure with a bottom opening considerably less than the opening of the top.

To one of the sides, as 15, is hinged a bottom 17, its edges preferably forming a polygon of the same number of sides as the sides of the display, and the edges of the bottom having flaps 18, 19 and 20 each formed with oppositely notched adjacent ends 21 and 22 forming overlapping and underlapping shouldered extremities respectively so arranged that when the flaps are brought together by moving the bottom downwardly within the sides, the notched shoulders or extremities 21 and 22 of the flaps will inter-engage and interlock forming a flaring cup, the upper edge of which is considerably larger in size than the opening at the bottom of the sides so that the more firmly the bottom is pressed downwardly the more firmly will be the engagement of the flaps and the more the bottom structure will be supported by the sides. The overlapping shouldered ends 21 and 22 each engage the opposite end of the adjacent flap at their shortest portion and the end of the lapping portion engages the corresponding side of the display so that the interlocking of the shoulders is substantially medially of the ends of the inter-engaging flaps, thus

forming a substantially irreducible flaring rim by the inter-engagement of the said flaps and the ends abutting the sides of the display to prevent further downward movement.

In order to release the bottom from such engagement it is simply pressed upwardly from the lower side which releases the engagement of the flaps, allowing them to spring apart by their own resilience.

- 10 In a six-sided figure as shown in the drawing, the bottom will collapse between the connected sides 10, 11 and 12 at one side of the bottom, and the sides 14, 15 and 16 at the other side of the bottom so that the structure will fold compactly for shipping and storage.

15 In order to insure that the bottom will remain in its set up or unfolded condition, a projection or tab 24 is formed as an extension at one edge of the bottom by cutting it out of the tab 20 and the lower edge of the opposite side 10 may be provided with a bottom notch 25 which engages this tab when the bottom is pressed down sufficiently as shown in detail in Fig. 4. To disengage this tab there is sufficient yielding of the sides of the basket so that if the bottom of the side 10 at the edges of the notch 25 are sprung outwardly, the tab 24 may be disengaged therefrom, allowing the bottom to spring or be pressed upwardly.

20 With this construction the bottom tabs overlap for interengagement with each other, there is no end to end abutment of the tabs with each other, and there is no hooked engagement of any of the tabs with the sides of the basket. Since this interlocking engagement is produced by 25 rounded shoulders at the ends of the tabs there is no tendency to break the shoulders and sufficient movement is possible in the engagement of these shoulders to permit a variation of the en-

gagement of the tabs, allowing a sliding movement of them as they are drawn together by a downward movement of the bottom within the sides.

I claim:

1. A folding basket display comprising connected wall sections of sheet material tapered toward but open at the bottom, a bottom hinged at the lower edge of one wall section, having separate marginal flaps with inter-engaging opposite shoulders formed intermediate the sides of each end adapted to abut, overlap and interlock at the ends of the flaps to provide outwardly flaring irreducible sides, a shoulder portion of the end of one flap engaging the opposite corresponding shoulder portion of the end of the next flap, and the overlapping extremities of both overlapping flaps engageable with the lower portions of the adjacent corresponding outer wall sections to prevent downward movement of the bottom, the inter-engaging flaps forming an irreducible upwardly flaring cup which wedgingly engages the wall sections near the bottom thereof and prevents the bottom from slipping through the opening at the lower end of the connected wall sections. 10

2. A structure in accordance with claim 1 in which the bottom having overlapping and interlocking sections formed of sheet material tend to spring upwardly free from distending engagement with the bottom of the basket, and the bottom being provided with a projection at the lower end of the flap in raised position engageable with the lower edge of one of the wall sections to lock the bottom against upward movement.

HENRY ZIEMMERMAN.
